(57) **CLAIM**

The ornamental design for a bow storage apparatus, as shown and described.

DESCRIPTION

FIG. 1 is a perspective view of the bow storage apparatus showing my design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a front view of the bow storage apparatus showing a bow stored thereon.

The features presented in broken lines are for environmental purposes only and form no part of the claimed design.
